UNITED STATES PATENT OFFICE

DAVID STROMBERG, OF CLEVELAND, OHIO, ASSIGNOR TO JOSEPH KORACH COMPANY, OF CLEVELAND, OHIO, A CORPORATION OF OHIO

DESIGN FOR A SHOW CARD

Application filed July 27, 1931. Serial No. 40,694. Term of patent 14 years.

To all whom it may concern:

Be it known that I, DAVID STROMBERG, a citizen of the United States, residing at Cleveland, in the county of Cuyahoga and State of Ohio, have invented a new, original, and ornamental Design for a Show Card, of which the following is a specification, reference being had to the accompanying drawing, forming a part thereof.

In the drawing, the figure is a front elevation of a show card embodying my invention. The dominant feature of the card is the utilization of a panel, in which advertising material may be inserted, together with an illustration at one side of the panel, which refers to the advertising matter on the panel.

I claim:

The ornamental design for a show card substantially as shown and described.

DAVID STROMBERG.
